(57) **CLAIM**

I claim the ornamental design for a flip top closure, as shown and described.

DESCRIPTION

FIG. 1 is top perspective view of a flip top closure;
FIG. 2 is a bottom perspective view of the flip top closure of FIG. 1;
FIG. 3 is a front view of the flip top closure of FIG. 1;
FIG. 4 is a back view of the flip top closure of FIG. 1;
FIG. 5 is a left side view of the flip top closure of FIG. 1;
FIG. 6 is a right side view of the flip top closure of FIG. 1;
FIG. 7 is a top view of the flip top closure of FIG. 1;
FIG. 8 is a bottom view of the flip top closure of FIG. 1;
FIG. 9 is across-sectional view of the flip top closure of FIG. 1 taken in the direction of line 9-9 in FIG. 7;
FIG. 10 is a top perspective view of the top closure of FIG. 1 shown in an open configuration;
FIG. 11 is a front perspective view of the flip top closure of FIG. 10;
FIG. 12 is a top view of the flip top closure of FIG. 10;
FIG. 13 is a bottom view of the flip top closure of FIG. 10;
FIG. 14 is a left side view of the flip top closure of FIG. 10;
FIG. 15 is a right side view of the flip top closure of FIG. 10;
and,
FIG. 16 is a cross-sectional view of the flip top closure of FIG. 10 taken in the direction of line 16-16 in FIG. 12.
The broken dot-dash lines identify planes from which cross-sectional views are taken and form no part of the claim.
